UNITED STATES PATENT OFFICE.

NICHOLAS BARRY, OF MUSCATINE, IOWA, ASSIGNOR TO BARRY COMPANY, OF MUSCATINE, IOWA, A CORPORATION OF IOWA.

SHEET-METAL PULLEY.

1,177,565.

Specification of Letters Patent. Patented Mar. 28, 1916.

Application filed August 10, 1914. Serial No. 856,054.

To all whom it may concern:

Be it known that I, NICHOLAS BARRY, a citizen of the United States, residing at Muscatine, in the county of Muscatine and State of Iowa, have invented certain new and useful Improvements in Sheet-Metal Pulleys; and I hereby declare that the following is a full, clear, and exact description thereof, reference being had to the accompanying drawings, which form part of this specification.

This invention relates to metal split pulleys, and its object is to produce an all metal split pulley which will have all the advantages of lightness possessed by wooden split pulleys, all the advantages of strength of metal pulleys, and can be economically made by stamping the parts out of sheet metal.

Important novel features of my pulley are (1) a hexagonal hub preferably formed of pieces of pressed sheet steel riveted or welded together; (2) tubular spoke members, also made out of pressed sheet steel, welded or riveted to the hub members and to the rim members; (3) rim members, also made of pressed sheet steel, provided with inturned tubular beads or flanges on their side edges giving the same great strength while preserving lightness thereof; (4) hollow reinforces or braces for the rim members, also made of pressed sheet steel and which also provide an efficient means for connecting the spoke members to the rim; (5) flush abutting joints at the ends of the rim sections formed by metal reinforcements or fillets connected to the ends of the rim sections in a peculiar manner and imparting great strength and rigidity to the rim sections at the joints.

Another very important and novel feature of the invention is that each pulley section as a whole is dipped in molten metal in order to unite the parts more securely, give them increased strength, close any open seams or joints, and to prevent rusting thereof.

The invention will be explained with reference to the accompanying drawings to enable others to manufacture and use the same; and the novel features and combinations of parts for which protection is desired are set forth in the claims.

In said drawings: Figure 1 is a side view 55 of the complete pulley as secured to a shaft.

Fig. 2 is an enlarged side view of one half of the pulley detached. Fig. 3 is an enlarged transverse sectional view on the line 3—3, Fig. 2. Fig. 4 is a section on line 4—4, Fig. 2. Fig. 5 is an enlarged detail section on line 5—5, Fig. 2. Fig. 6 is an inner face view of one of the pulley sections. Fig. 7 is a detail section on line 7—7, Fig. 2. Fig. 8 is a side view of a clamp member, partly broken. Fig. 9 is a bottom view of the clamp. Fig. 10 is a section on line 10—10, Fig. 5. Fig. 11 is a detail view of one of the joints between the rims of two of the pulley halves. Fig. 12 is a section on line 12—12, Fig. 5.

The pulley is made in two diametrically parted halves each of which is similarly constructed, and I will describe one half in detail; thus explaining both.

The rim 1 is preferably made of sheet 75 steel and pressed into semi-circular form longitudinally. The outer edges of the rim are preferably provided with inwardly projecting tubular beads 1^a which are formed by bending the edges of the rim longitudinally upon themselves so that the extreme outer edges of said rim are inturned against the rim, as shown at 1^b, Fig. 5; and such bead is flattened laterally so as to be of greater depth than width and thus forms a 85 strong integral tubular flange on the edges of the rim, imparts great strength and stiffness to the rim and enables the pulley to withstand greater pressure and even ordinary blows on the edge of the rim without 90 injury.

Within the rim is a circumferential centrally disposed tubular arch or reinforce 2 which preferably consists of a strip of sheet steel bent into an arch or U-form in cross 95 section; the outer flanges 2^a of this reinforce being united to the inner face of the rim section in any suitable way preferably by welding; I preferably electrically spot weld the rim and reinforce together as indicated at 100 2^w in the drawings, thus rigidly and permanently uniting them. This reinforce 2, greatly strengthens and stiffens the rim and makes it practically unyielding both transversely and radially or circumferentially.

Each pulley section has a plurality of spoke members and in the pulley shown there are three spoke members attached to each section. Each spoke member 3 is preferably stamped from sheet steel and bent 110

into oval shape in cross section, and slightly tapered from the hub outward. The outer end of each spoke member is secured to the rim, preferably by fitting it into openings in the reinforce 2 surrounded by flanges 2^a, Figs. 3 and 6. The spoke members being preferably united to the reinforce by electrically spot welding the spoke members to flanges 2^a as indicated at 3^w for purpose of cheapness and rigidity.

The hub end of each spoke member is fitted within outwardly projecting flanges 5 on the hub member which hub member is preferably composed of two similar but opposite pressed steel plates that are preferably bent angularly to fit over removable bushings B surrounding the shaft S on which the wheel is mounted (Fig. 1) each plate has a base or major flange portion 5^a extending parallel with the shaft and has radially extending flanges 5 which are adapted to fit around and receive the inner ends of the spoke members 3; and are rigidly attached to the spoke members preferably by spot welding as indicated at 3^w. The flanges 5 are connected together intermediate the spokes by webs 5^b which are preferably spot welded as indicated at 5^w. The hub member is also provided at its opposite ends with projecting flanges 5^c which are provided with openings for the passage of the bolts 8 by which the sections are clamped together, as hereinafter explained.

The hub flanges 5^a are adapted to fit over a removable bushing B which is externally shaped to fit the hub and is internally bored to fit the shaft S on which the pulley is to be mounted; the bushings B are removable, and interchangeable, so that the pulley can be fitted to any different sized shaft by providing same with a suitable bushing. Preferably the spoke members 3 are provided with longitudinal pressed ribs 3^a on their outer sides to impart additional strength and stiffness thereto.

In order to securely unite the abutting ends of the rim members when the pulley halves are secured to the shaft a plate 7^a of stamped sheet metal is attached to each end of the rim members as shown in Figs. 5, 6, 10 and 11. Such plate is preferably L-shaped in cross section and has its outer flange 7^a fitted against the inner face of the rim and secured thereto by spot welding as at 7^w and the end of the rim is flanged over the bend of this plate 7 as at 1^w and this may be welded or soldered together. The end of the reinforce 2 is shouldered as at 2^x (Fig. 12) to fit over the member 7^a, and 60 may be spot welded thereto as shown at 1^w, and the other flange 7^a of this plate which lies in about the diametrical plane of the pulley and may be provided with a central projection 7^c fitting over the bend of the reinforce 2 and may be spot welded thereto as

at w, see Figs. 10 and 11. The flange 7^c may be provided at each side of the reinforce with perforations 7^e for the passage of securing bolts 9 which transfix the opposed plates on the pulley sections and are secured by nuts 9^a firmly clamping the abutting ends of the rim together.

After the pulley sections are made they are preferably dipped in molten tin or other suitable metal or composition of metals, 75 which fills the crevices at the bends and joints and renders the surface of the pulley smooth and practically solders the parts together and protects the parts against rust. The parts being preferably connected by 80 electric spot welding some slight crevices may be left between the unwelded portions, and any such crevices will be filled by the molten metal in the soldering process, thus producing a close joint and preventing looseness of parts. This soldering strengthens the pulley approximately 20 to 30 per cent., and the weight of the pulley is decreased as compared with a wooden pulley of given strength and size and as compared with ordinary metal pulleys. Such soldered pulleys are especially useful where exposed to dampness or to action of gases which would be detrimental to ordinary pulleys, or where exposed to the weather. Soldering or tinning and spot welding practically renders my sheet metal pulley equivalent to an integral metal pulley, and it can be made as light as a wooden pulley of the same size. The pulleys may be even lighter than 100 wooden pulleys for in actual practice a twenty-four inch pulley four inch face made in accordance with my invention will weigh about sixteen pounds, whereas a wooden pulley of the same size would weigh about 105 thirty pounds.

When the pulley is mounted upon a shaft the opposite pulley halves are securely clamped to the bushing and shaft and to each other by means of clamps composed of opposite members 6, preferably made of stamped metal, each provided in its inner side with a polygonal recess adapted to fit over the flanges 5 of each hub section. The clamp member is also provided at each end with projecting portions 6^a which are provided with apertures 6^b for the passage of the retaining bolts 8. The ends 6^c of the side walls of the clamp member are bent inwardly, as shown in Fig. 9, to close the ends of the clamp, and impart additional strength to the clamp; as compared with the open ended clamps which have been heretofore made from sheet metal. By means of these clamps the pulley halves can be securely fastened on the shaft. The polygonal shape of the recesses in the clamp members prevents the clamps slipping circumferentially on the hub. These clamps are applied to each end of the hub of the pulley and will 120 125 130

securely clamp the pulley in position upon the shaft.

A pulley constructed as described has all the advantages of the wooden split pulley as regards lightness and ease of placing same upon a shaft; it will not rust nor corrode; the rim will not separate at the joints; the hub being hexagonal avoids all possibility of slip between the pulley and the bushing and clamps; the spoke members being hollow and made in one piece are very strong; and the rim being beaded and reinforced as described is stiff and strong; and the pulley halves can be very readily applied to a shaft or removed therefrom.

In the specification and claims the word solder or soldered is intended to cover dipping the pulley sections in molten tin or other suitable metal or composition of metals, or so applying such hot metal to the parts as will effectively close the joints and crevices between the connected pieces and firmly bond them together thus making the parts almost homogeneous and capable of withstanding great strain without injury and contributing most materially to the durability and serviceability of the pulley.

What I claim is:

1. In a metal split pulley, a rim member formed of sheet metal, a reinforce extending circumferentially of and within said rim member, said reinforce being arched in cross section and having outwardly extending flanges secured to the rim by electric welds and solder; with a hub member, and tubular spoke members connected to the hub member and to said reinforce by spot welds and solder.

2. In a metal split pulley, a rim member formed of sheet metal, and a reinforce extending circumferentially of and within said rim member, said reinforce being arched in cross section; with an angular plate attached to each end of the rim member and having an inwardly projecting flange overlying the end of the reinforce and having a lug attached to said reinforce, substantially as described.

3. In a metal split pulley, a rim member formed of sheet metal, and a reinforce extending circumferentially of and within said rim member, said reinforce being arched in cross section and having outwardly extending flanges secured to the rim; with an angular plate attached to each end of the rim member, the ends of the rim member being bent over said angular plates, said plates overlying the ends of the reinforce and having outwardly projecting lugs attached to said reinforce, substantially as described.

4. In a pulley a hub member, a rim member formed of sheet metal, and a reinforce extending circumferentially of and within said rim member and arched in cross section and provided with flanged openings to

engage the spokes, with tubular spoke members connected to the hub member and having their outer ends entered in the openings in said reinforce and secured thereto.

5. In a metal split pulley, a hub member, a rim member formed of sheet metal, and a reinforce extending circumferentially of and within said rim member, said reinforce being arched in cross section and provided with flanged openings to engage the spokes; with tubular spoke members connected to the hub member and having their outer ends entered in the openings in said reinforce and secured to the hub and reinforce by spot welds.

6. In a metal split pulley, a rim member having a hollow reinforce provided with flanged openings to receive the outer ends of the spokes, a hub member composed of opposite similar plates having flanges extending longitudinally of the shaft and radially disposed flanges forming sockets adapted to receive the inner ends of the spokes, and hollow spoke members engaging the sockets in said reinforce and the hub member.

7. In a metal split pulley, a hub member composed of opposite similar plates having flanges extending longitudinally of the shaft and radially disposed flanges forming sockets adapted to receive the inner ends of the spokes, said plates being united by spot welds; with a rim member having a hollow reinforce provided with flanged openings to receive the outer ends of the spokes and hollow spoke members engaging the sockets in said reinforce and the hub member and secured thereto by spot welds, substantially as described.

8. In a metal split pulley, a sheet metal rim section and an angular plate secured to each end of the section, the ends of the rim section being turned inward over the bends of such plates.

9. In a metal split pulley, a sheet metal rim section, and an angular plate secured to each end of the rim section and having an inwardly projecting flange provided with perforations for the engagement of securing bolts the ends of the rim section being turned inward over the bends of said plates.

10. A rim section for metal split pulleys, formed of sheet metal and having its side edges bent inwardly to form tubular beads; with an angularly bent plate attached to each end of the rim section, for attachment to a similar opposed rim section, the ends of the rim section being bent inwardly over said plates.

11. A metal pulley comprising hub, spoke and rim members formed of separate pieces of sheet metal rigidly connected together, and the joints between the pieces closed by solder substantially as specified.

12. A metal pulley comprising hub, spoke

and rim members formed of separate pieces of sheet metal rigidly connected together by electric spot welds and solder, substantially as specified.

- 5 13. A metal split pulley composed of opposite halves each formed of separate pieces of sheet metal rigidly connected at intervals, and the joints between the pieces closed by solder, substantially as specified.
- 10 14. A metal split pulley composed of opposite halves each comprising hub, spoke and rim members formed of separate pieces and rigidly united by electric welds and solder, substantially as specified.
- 15 15. A metal split pulley composed of opposite sections each comprising a hub portion formed of separate pieces, spokes and rim members formed of separate pieces of sheet metal, all united together by electric welds and solder, substantially as specified.
- 20 16. In a metal pulley, a rim having its side edges bent inwardly upon themselves to form tubular stiffening beads, and a reinforce extending circumferentially of and within said rim member, said reinforce being arched in cross section and having outwardly extending flanges secured to the rim at intervals and the joints or crevices therebetween closed by solder, substantially as described.
- 25 17. In a metal pulley, a rim having its side edges bent inwardly upon themselves to form tubular stiffening beads, and a reinforce arched in cross section and extending circumferentially of and within said rim member and having outwardly extending flanges secured to the rim at intervals by electric spot welds, the whole being soldered to close the joints therebetween, substantially as described.
- 30 18. A metal split pulley comprising a hub member composed of opposite similar plates having angularly bent portions extending circumferentially and longitudinally of the shaft and radially disposed flanges at the inner ends of said portions bent at intervals to form spoke sockets; in combination with a rim member, and tubular spokes, said spokes being rigidly connected at intervals to the rim and hub members and the whole soldered to close all joints between the parts intermediate the connections and bond them together, substantially as described.
- 35 19. A metal split pulley comprising a hub member composed of opposite similar plates having angularly bent portions extending circumferentially and longitudinally of the shaft radially disposed flanges at the inner ends of said portions bent at intervals to form spoke sockets; in combination with a rim member, and tubular spokes, said spokes being rigidly united to the rim and hub members by electric spot welds, and the whole soldered to close all joints between the welds.

20. A metal split pulley comprising a hub member composed of opposite similar sheet metal plates having angularly bent portions extending circumferentially and longitudinally of the shaft and having radially disposed flanges on their inner ends bent radially at intervals to form sockets for the inner ends of the spokes, said plates being united by electric spot welds, a rim member having an arched reinforce provided with openings for the ends of the spokes, and tubular spokes secured to the radial flanges of the hub member at their inner ends and to the said reinforce at their outer ends, said spokes being united to said reinforce and to the hub members by electric welds and the whole soldered to close all the joints between the welds.

21. A metal split pulley comprising a hub member composed of opposite similar sheet metal plates having angularly bent portions extending circumferentially and longitudinally of the shaft and having radially disposed flanges on their inner ends bent radially at intervals to form sockets for the inner ends of the spokes, said plates being connected at intervals; with a rim member having an arched reinforce provided with openings for the ends of the spokes, and tubular spokes secured to the radial flanges of the hub member at their inner ends and to the said reinforce at their outer ends, said spokes being united to the reinforce and hub members and the whole soldered to close all joints intermediate the connections and bond them together.

22. In a metal split pulley, a hub member, and a rim member, each formed of sheet metal with hollow spoke members each formed of a single piece of sheet metal bent to form a tubular spoke, and secured to the hub and rim member by spot welds and the whole soldered to close all joints between the welds.

23. In a metal split pulley, a rim member having a hollow reinforce provided with flanged openings to receive the outer ends of spokes, a hub member having flanges extending longitudinally of the shaft and radially disposed flanges forming sockets adapted to receive the inner ends of the spokes, and hollow spokes connected to the flanges of said reinforce and the hub member and the whole soldered to close all joints and bond the parts together, substantially as described.

24. In a metal split pulley, a rim member formed of sheet metal, and a reinforce extending circumferentially of and within said rim member, said reinforce being arched in cross section and having outwardly extending flanges, said reinforce being secured to the rim by electric spot welds and solder, substantially as described.

25. For a metal split pulley, a hub mem-

ber composed of opposite similar plates having flanges extending longitudinally of the shaft and radially disposed flanges adapted to receive the ends of the spokes, said sections being rigidly united together by electric spot welds and solder, substantially as described.

26. A metal split pulley comprising a hub member composed of opposite similar plates having angularly bent portions extending circumferentially longitudinally of the shaft and radially disposed flanges at the inner ends of said portions bent at intervals to form spoke sockets; in combination with a rim member, and tubular spokes said spokes being rigidly united to the rim and hub members by electric spot welds and solder.

27. A metal split pulley comprising a hub member composed of opposite similar sheet metal plates having angularly bent portions extending circumferentially and longitudinally of the shaft and having radially disposed flanges on their inner ends bent radially at intervals to form sockets for the inner ends of the spokes, said plates being united by electric spot welds; with a rim member having an arched reinforce provided with openings for the ends of the spokes, and tubular spokes secured to the radial flanges of the hub member at their inner ends and to the said reinforce at their outer ends; said spokes being united to the reinforce and hub members by electric welds.

28. In a metal split pulley, a hub member, and a rim member each formed of sheet metal, with hollow spoke members each formed of a single piece of sheet metal bent to form a tubular spoke, and secured to the hub and rim member by spot welds.

29. In a metal split pulley, a rim member having a hollow reinforce provided with flanged openings to receive the outer ends of spokes, a hub member having flanges extending longitudinally of the shaft and radially disposed flanges forming sockets adapted to receive the inner ends of the spokes, and hollow spokes connected to the flanges of said reinforce and the hub member by spot welds.

30. A rim section for metal split pulleys formed of sheet metal and having its side edges bent to form tubular beads, and sheet metal plates bent longitudinally upon themselves and attached by one side flange to the end of the rim member and having its other side flange projecting inwardly at right angles to the rim intermediate the beads for attachment to a similar rim section.

31. In a sheet metal pulley a rim section having its edges turned in to form tubular beads, the inner edge of each bead having a flattened portion lying flat against the inside of the rim and soldered thereto.

32. In a metal split pulley, a rim formed of sheet metal, a reinforce extending cir-

cumferentially of and within said rim member, said reinforce being arched in cross section and having outwardly extending flanges lying flat against the rim section; with a hub member, and tubular spoke members united to the hub member and to the reinforce said parts being also soldered together.

33. In a metal split pulley, a rim member formed of sheet metal, and a reinforce extending circumferentially of and within said rim member, said reinforce being arched in cross section; with an angular plate united to each end of the rim member and having an inwardly projecting flange overlying the end of the reinforce and a lug united to the reinforce, the parts being also soldered together.

34. In a pulley, a hub member, a rim member formed of sheet metal, and a reinforce extending circumferentially of and within said rim member and arched in cross section and provided with flanged openings to engage the spokes, with tubular spoke members connected to the hub member and having their outer ends entered in the openings in said reinforce and united thereto said parts being also soldered together.

35. In a metal split pulley, a sheet metal rim section, and an angular plate secured to each end of the rim section and having perforations for the engagement of securing bolts in its inwardly projecting flanges the end of said rim section being turned inward over the bends of said plates, and united thereto and said parts being also soldered together.

36. In a metal split pulley, a rim member having a hollow reinforce provided with flanged openings to receive the outer ends of the spokes, a hub member composed of opposite similar plates having flanges extending longitudinally of the shaft and radially disposed flanges forming sockets adapted to receive the inner ends of the spokes, said plates being united and being also soldered together, and hollow spoke members engaging the sockets in said reinforcements and hub member.

37. In a metal split pulley, a rim formed of sheet metal, a reinforce extending circumferentially of and within said rim member, said reinforce being arched in cross section and having outwardly extending flanges lying flat against the rim section and being secured thereto by spot welds and solder; with a hub member, and tubular spoke members united to the hub member and to the reinforce by spot welds and solder.

38. In a metal split pulley, a rim member formed of sheet metal, and a reinforce extending circumferentially of and within said rim member, said reinforce being arched in cross section; with an angular plate, united in each end of the rim member by spot welds and solder, and the angular

plate having an inwardly projecting flange overlying the end of the reinforce and having a lug united to the reinforce by spot welds and solder.

5 39. In a pulley, a hub member, a rim member formed of sheet metal, and a reinforce extending circumferentially of and within said rim member, and arched in cross section and provided with flanged openings 10 to engage the spokes, with tubular spoke members connected to the hub member and having the outer ends entered in the openings in said reinforce and united thereto by spot welds and solder, substantially as described.

40. In a metal split pulley, a sheet metal rim section, and an angular plate secured to each end of the rim section and having perforations for the engagement of securing 20 bolts in its inwardly projecting flanges, the end of said rim section being turned inward over the bends of said plates, and united thereto by spot welds and solder, substantially as described.

25 41. In a metal split pulley, a rim member having a hollow reinforce provided with flanged openings to receive the outer ends of the spokes, a hub member composed of opposite similar plates having flanges extending longitudinally of the shaft and ra-

30 dially disposed flanges forming sockets adapted to receive the inner ends of the spokes, said plates united together by spot welds and solder, and hollow spoke members engaging the sockets in said reinforcements and hub member.

42. In a pulley, a rim member formed of sheet metal and having its side edges bent upon themselves to form tubular reinforcing beads or flanges, the extreme outer edges of said rim being inturned within the bead and lying parallel with and against the inner surface of the rim.

43. In a sheet metal pulley, a rim member formed of sheet metal and having its side 45 edges bent upon themselves to form tubular reinforcing beads or flanges, the extreme outer edges of said rim being inturned within the beads and lying against the inner surface of the rim; said beads being of greater thickness radially of the pulley than transversely thereof.

In testimony that I claim the foregoing as my own, I affix my signature in presence of two witnesses.

NICHOLAS BARRY.
